DESIGN FOR AN EGG DISH

Matthew H. Shulman, New York, N. Y.

Application January 26, 1944, Serial No. 112,342

Term of patent 7 years

(Cl. D44—15)

To all whom it may concern:

Be it known that I, Matthew H. Shulman, a citizen of the United States and resident of New York, in the county of New York and State of New York, have invented a new, original, and ornamental Design for An Egg Dish, of which the following is a specification, reference being had to the accompanying drawing, forming a part thereof, and of which Fig. 1 is a perspective view of an egg dish showing my new design; and Fig. 2 is a vertical sectional view thereof.

I claim:

The ornamental design for an egg dish, substantially as shown.

MATTHEW H. SHULMAN.
